UNITED STATES PATENT OFFICE.

GEORGES CARETTE, OF NUREMBERG, GERMANY.

PICTURE-HOLDING DISK FOR MAGIC LANTERNS.

SPECIFICATION forming part of Letters Patent No. 376,631, dated January 17, 1888.

Application filed July 27, 1887. Serial No. 245,449. (No model.)

To all whom it may concern:

Be it known that I, GEORGES CARETTE, a subject of the Emperor of Germany, and a resident of Nuremberg, Germany, have invented new and useful Improvements Relating to Magic Lanterns, of which the following is a specification, reference being had to the accompanying drawings.

My invention relates to means for changing the pictures in magic lanterns.

In the magic lanterns heretofore constructed means have not been provided by which the easy and convenient insertion of the pictures can be effected.

The device hereinafter described is intended to make good this deficiency, and has the advantage that even children can, without any previous training, project pictures correctly and accurately upon a wall or screen. The said device is also of great value when taking into consideration that in the neighborhood of the lamp everything must remain dark. The said device comprises a revolving disk which is adapted to receive three or more pictures, according to the size, and which is fixed by means of a spring engaging with the notches of a small notched wheel just when the axis of a picture coincides with the axis of the lens.

In the accompanying drawings, Figure 1 is a front view of the magic lantern. Fig. 2 is a part section through the center of the lens. Fig. 3 is a section on the line xx , Fig. 2, showing the disk mechanism as seen from the rear.

Like letters of reference indicate corresponding parts throughout the figures.

The construction of the magic lantern does not materially differ from those heretofore used.

A designates the lantern-casing; B, the lamp; C, the lens-tube.

In carrying my invention into practice a revolving disk, D, is carried on an axis, d, one end of which is supported in the front of the lamp-casing, while the other end is carried in the bracket f, fixed below the lens-tube. The said tube is cut away at e in order to enable the said disk to enter.

The revolving disk D is provided with three or more pockets, e e', according to its size,

which are formed by soldering folds upon the said disk. Into these pockets the glass pictures, made in the usual manner, are slid, and can be easily taken out when required. Upon the axis d, and firmly connected with it, is a small notched wheel, g, having just as many notches as there are pockets upon the revolving disk—according to the drawings four.

A spring, i, is adapted to engage with the notches of the small notched wheel g, and acts as a pawl to prevent the revolving disk D from turning until a force sufficient to overcome the force of the spring i presses the said spring out of engagement with the notched wheel.

Fig. 1 shows the position of the disk when the spring i has fallen into one of the notches of the wheel g, and Fig. 2 shows the position of the disk D when it has been turned so far that the spring is between two notches.

The disk is so arranged that the center of the pockets and that of the picture fitted therein coincide with the center of the lens when, as in Fig. 1, the spring i engages with one of the notches of the small notched wheel g, thus acting as a brake to hold the disk in this position until released, as above described. A new glass picture can then be slid in upon one of the side pockets, e, and the picture just presented can be removed from the opposite pocket, e'. For presenting a new picture it is only necessary to turn the disk at the periphery till the spring i, that is thereby lifted out, falls into the succeeding notch, whereupon, in the manner above described, a new picture is inserted in the side pocket at e, and the picture e' on the opposite side, just exhibited, can be easily taken out.

The working of the lantern is so exceedingly simple that it can be performed by a child, it being at the same time certain that the pictures are put in in the most accurate manner without any previous experience, and not only in the center, but also with regard to their distance relatively to the lenses, so that the troublesome adjustment of the lenses after every change of the picture is avoided.

For presenting moving pictures upon long glass plates, the usual enlargement, h, is provided in the lens-tube C.

What I claim is—

In a magic lantern, the combination of the disk D, provided with pockets *e e'*, for the reception of the pictures, the notched wheel *g*, 5 mounted on the axis of the disk D, and the spring *i*, engaging with the notches of the notched wheel, substantially as described.

In testimony whereof I have hereunto signed my name in the presence of two subscribing witnesses.

GEORGES CARETTE.
